CLAIM

The ornamental design for a ball light, as shown and described.

DESCRIPTION

FIG. 1 is a top, front and right side perspective view of a ball light showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 1.

The evenly dashed broken lines illustrate portions of the ball light. The unevenly dashed broken lines define the boundaries of the enlarged view. None of the broken lines form part of the claimed design.
